UNITED STATES PATENT OFFICE

2,475,088

AIR CIRCULATING RADIATOR

Robert G. Fisher, Coplay, Pa.

Application March 25, 1947, Serial No. 737,181

2 Claims. (Cl. 257—137)

1

My invention relates to improvements in heating radiators having air circulating means.

A primary object of the invention is to provide a radiator of the above mentioned class, which is simplified in design, and therefore easy and very economical to fabricate.

A further object is to provide a heating radiator having novel means for circulating heated air in a room.

A still further object is to provide a radiator of the class mentioned, having means to circulate warm air during the winter, and cool air during the summer, and which is adapted to employ either steam or hot water for a heating medium.

A further object is to provide a radiator of welded construction, provided with air heating ducts, such ducts being in direct thermal contact with a heating surface of the radiator.

Other objects and advantages of the invention will be apparent during the course of the following description.

In the accompanying drawings forming a part of this application, and in which like numerals are employed to designate like parts throughout the same,

Figure 1 is a perspective view of the radiator and radiator cover, and showing an associated fan,

Figure 2 is a perspective view of the radiator with the radiator cover removed,

Figure 3 is a horizontal section taken on line 3—3 of Figure 2,

Figure 4 is a vertical section taken on line 4—4 of Figure 1,

Figure 5 is a vertical longitudinal section taken on line 5—5 of Figure 3,

Figure 6 is a perspective view of air ducts removed, and

Figure 7 is a vertical detail section taken on line 7—7 of Figure 3.

In the drawings where for the purpose of illustration is shown a preferred embodiment of my invention, the numerals 10 and 11 designate lower and upper reservoirs or headers respectively. Each of these headers 10 and 11 includes a horizontal section of standard structural channel iron 12, which forms the body member of the header. The channel sections 12 of the headers are U-shaped, and their main horizontal webs 12' are disposed inwardly in opposed relation with respect to the top and bottom of the radiator. The channel section 12 of each header is provided with a plurality of parallel longitudinal rows of spaced circular openings 13, three longitudinal rows being satisfactory. The openings 13 of

2

the two channel sections 12 are in vertical alignment and receive the opposite ends of vertical cylindrical tubular columns or pipes 14 within them, see Figure 4. These pipes 14 are securely welded in place within the openings 13, and form liquid tight joints with the channel sections 12. The pipes 14 thus welded in place tie the channel sections 12 of the headers 10 and 11 together to form a rigid structure. The outer open sides of 10 the channels 12 are covered with sheet metal strips 15. These sheet metal strips 15 are welded to the outer longitudinal edges of the side vertical webs of the channel sections, for the full length of the same, and formed therewith a liquid tight 15 connection. The strips 15 form the bottom and top of the lower and upper headers respectively. The open ends of the lower and upper headers are covered with sheet metal strips 16, securely welded to the ends of the channel sections 12 20 and also to the ends of the strips 15. These welded connections are also liquid tight. It is thus seen that a heating radiator structure is provided comprising the lower and upper horizontal headers 10 and 11, and the vertical pipes or columns 14. The two headers are in communication through the pipes 14, and the radiator structure is adapted to be used with steam or water as the heating medium.

In the drawings, the radiator is illustrated as 30 a steam radiator, and the lower header 10 is provided with a steam inlet pipe 17 passing through an opening in one of the ends 16 of such header. The pipe 17 forms a liquid tight joint with the end 16 of the lower header.

The radiator is provided with four legs 18, arranged at the corners of the radiator, and these legs are welded to the bottom of the lower header 10 directly beneath the vertical side webs of the channel section 12 of that header. With this 40 arrangement, the side webs of the channel section support the weight of the radiator, rather than the thin sheet metal strip 15 of the bottom header. The legs 18 may be made from sections of standard structural angle iron of suitable size, 45 cut in equal lengths. The legs 18 of course, maintain the radiator spaced slightly above the floor.

At the end of the radiator, remote from the 50 inlet pipe 17, is an air fan 19, supported by any suitable means, and adapted to be driven by an electric motor, not shown. The intake or suction side of the fan 19 may be connected to a fresh air duct beneath the floor of the room, or it may take in air directly from the room, as desired. The discharge side of the fan 19 is con-

nected to an air duct 20, leading to the adjacent end of the radiator. This air duct 20 is connected with a transverse air duct section 21 disposed upon the top surface of the bottom header. The air ducts 20 and 21 are formed of sheet metal, and they are rectangular in cross-section. The transverse air duct 21 leads, at its opposite ends, into parallel longitudinal rectangular branch air ducts 22, also disposed upon the upper surface of the lower header 10, and in direct thermal contact therewith. The bottoms of the air ducts 21 and 22 may be tacked, or spot welded at intervals to the upper surface of the header 10, to permanently connect them with the header. The branch ducts 22 are closed at their ends 22', remote from the transverse duct 21. The branch ducts 22 are rectangular in transverse cross section, and are provided with removable and interchangeable sliding tops or covers 23. To allow this, the vertical sides 24 of the branch ducts 22 are provided with upper longitudinal horizontal flanges 25, extending for the full length of the branch ducts. These removable sliding covers 23 have short integral depending sides 26, provided with inwardly projecting horizontal longitudinal flanges 27, to slidably engage beneath the flanges 25. The covers 23 may also be provided with a handle extension 28, formed integral therewith, to facilitate the removal of the sliding covers. The removable covers 23 are provided with a plurality of longitudinally spaced openings 29 for the passage of air outwardly from the branch ducts, and the size and shape of these openings 29 may be varied on different covers, as desired. During the winter, when heated air is being circulated through the radiator pipes and room, it is desirable to use a cover 23 having a plurality of small air discharge openings 29, and during the summer when it is desired to circulate cool air through the room, a cover 23 is employed having larger air discharge openings or slots.

Particular attention is called to the arrangement of the ducts 21 and 22 upon the top surface of the lower header 10, to provide a large area of contact between the ducts and the header. This results in the efficient heating of the air within the ducts 21 and 22 by thermal conductivity, as well as by radiation from the pipes 14 and headers, after the air discharges through the openings 29.

This radiator provides a very large surface or area for radiation, and the headers 10 and 11 as well as the pipes 14 make up such heating surface.

When steam or hot water is introduced into the radiator it will radiate heat to a room, and when the fan 19 is started, and air under pressure is introduced into the ducts 21 and 22, such air will discharge through the openings 29 and circulate evenly through the room being heated. The radiator may be used with or without the fan in operation.

A rectangular radiator cover 30 is provided, and this cover is slipped over the radiator and rests directly upon the floor. The cover is not supported by the radiator, and it is open at the

bottom. The cover 30 is provided with suitable slots or air vents 31 in its sides, ends, and top, to allow free circulation of the air being discharged from the branch ducts 22 into the surrounding room.

The radiator is simple, compact, extremely economical to build, and provides an efficient heating and air circulating unit.

It is to be understood that the form of my invention herewith shown and described is to be taken as a preferred example of the same and that various changes in the shape, size, and arrangement of parts may be resorted to, without departing from the spirit of my invention or the scope of the subjoined claims.

Having thus described my invention, what I claim is:

1. An air circulating radiator, comprising elongated upper and lower headers, outer longitudinal rows of pipes connecting the headers and communicating therewith, an inner longitudinal row of pipes connecting the headers and communicating therewith and spaced from the outer rows of pipes, substantially horizontal elongated air ducts arranged between the outer and inner rows of pipes and in thermal contact with the top of the lower header, the air ducts extending for substantially the entire lengths of the inner and outer rows of pipes and being provided with longitudinally spaced air discharge openings in their tops, means to force air into the air ducts, and a cover to fit over the radiator and provided with air discharge vents.
2. An air circulating radiator, comprising elongated upper and lower headers, outer longitudinal rows of pipes connecting the headers and communicating therewith, an inner longitudinal row of pipes connecting the headers and communicating therewith and spaced from the outer rows of pipes, a substantially U-shaped air duct mounted upon the lower header and in thermal contact therewith, said U-shaped air duct including laterally spaced elongated branch ducts arranged between the inner and outer rows of pipes and extending for substantially the entire length of the inner and outer rows, said branch ducts being provided in their tops with longitudinally spaced air discharge openings, a fan to force air into the U-shaped air duct and a cover to engage over the radiator and provided with air discharge vents in its sides.
